Nicholas Muller of New York, N.Y. Des 2502

Letter's Patent No. 246,1. Date Oct. 31, 1866

Design for a Clock Case

The subject is referred to in this, Letter's Patent and making part of the same.

It all whom it may concern:

I, Nicholas Muller of 68 West 49th Street in the City, County, and State of New York have invented a new and Improved Design for Clock Case, and I hereby declare that the following is a full, clear and exact description thereof, which will enable others skilled in the art to understand the same, reference being had to the accompanying drawing forming part of this specification, in which:

Figure 1, represents a front elevation.

Figure 2, is a side elevation.

Similar letter of reference indicates like parts.

This invention relates to a Design for a clock case, the principal features of which consist in an ornate A, which forms the top of the case and which is provided with Greek handles or, said ornate ornament being of the shape of a B, of the case C, and said ornate ornament being decorated, C, on its ends and by an arabesque e, in the center.

The face of the case is ornamentally leaved d, and arabesque, when viewed from the side ornamenteby arabesque f, as shown in Figure 2. The lower part, or base of the case is composed of a square number g, a rounded number h, followed by a square number i, which surrounds a broad incline or conical number j.

This number rests upon the square number h, which is supported by the legs l. The numbers h, i, and j, and the legs l, are ornamented by arabesque, and between the legs in the middle of the front is an ornament m, which gives to the whole a rich and elegant appearance.

Having thus described my invention, I claim as new and distinctively:

Letter's Patent.

The Design for a Clock Case as shown and described.

The above specification of my invention signed by me this 26th day of September 1866.

Witnessed

John F. Mc Namara.

Nicholas Muller.
